UNITED STATES PATENT OFFICE

ARTHUR H. DU GRENIER, OF HAVERHILL, MASSACHUSETTS, ASSIGNOR, BY MESNE ASSIGNMENTS, TO CONSOLIDATED AUTOMATIC MERCHANDISING CORPORATION, A CORPORATION OF DELAWARE

VENDING MACHINE

Application filed April 26, 1928. Serial No. 104,853.

This invention relates to certain improvements in that class of vending or dispensing machines which are primarily designed to deliver articles packed in flat, square cornered cartons, and more particularly to that type of machine in which the cartons, ready for delivery, are placed in a stack, and the bottom carton of the stack is delivered when the machine is operated.

10 On account of the fact that these cartons are usually made of thin card board and are only partly filled, so that their contents does not assist in holding them in shape, considerable difficulty has been encountered in delivering the cartons from machines of the above described type, on account of the fact that they are liable to become distorted in shape. A more serious difficulty, however, is due to the fact that, on account of the size 15 of the carton, or package to be delivered, it has been found possible in many instances to pilfer the contents of such machines by removing the same thru the delivery passage.

The objects of my invention are to provide 20 a vending machine, for the purpose above referred to, which is adapted to deliver the packages, without damage thereto, or substantial distortion thereof, and to operate in a manner which will insure delivery, so long 25 as there are packages in the machine. Also to produce a machine which is provided with means arranged to prevent the removal of its contents thru the delivery passage without 30 operation of the coin-controlled mechanism 35 with which it is provided.

I accomplish these and other objects by means of the mechanism hereinafter described and illustrated in the accompanying drawings in which:

40 Fig. 1 is a perspective view of the outer casting of a vending machine embodying my invention.

Fig. 2 is a vertical sectional view thru the middle thereof.

45 Fig. 3 is a side elevation of the dispensing mechanism.

Fig. 4 is a detail view of a locking mechanism which is employed.

50 Fig. 5 is a plan view of the dispensing mechanism.

Fig. 6 is a central vertical sectional view thereof, showing the delivery tray in partly advanced position.

Fig. 7 is a similar view, showing the tray in its delivering position.

Fig. 8 is a detail sectional view at line 8-8 of Fig. 3.

As shown in the drawings, the casing 10 is constructed to provide a vertically extending rear portion adapted to receive a stack 60 of flat, square packages, as X, and a forwardly extending portion opening to a delivery chute 11 in its front end. A tray 12 is mounted in position to be reciprocated horizontally between a position beneath the 65 stack, and a position in front thereof, said tray being constructed to receive a single package, the sides of the tray being of the same height as the sides of the package and the internal dimensions of the sides being 70 slightly greater than length of the sides of the package, so that the latter may pass readily therein when in a horizontal, or nearly horizontal position. The frame within the casing is provided with horizontal guide 75 way slots 13, into which guide ribs 14, on the outer sides of the tray, project, permitting the tray to be moved between a filling position, directly beneath the stack, to a discharging position at the front end of the casing. A bottom 15 is provided for said tray, which is adapted to close the entire space enclosed by the sides thereof, and is pivotally connected to said sides by pivots 16 at the rear end thereof, so that it may swing down- 80 wardly to permit delivery of the package from the tray. A roller 17 is mounted on bearing pins 18 in the sides of the tray, directly above the rear side thereof, the upper portion of the roller being held at the level of 85 the upper edges of the sides of the tray and said roller extending the entire width of the package receiving chamber therein.

A rod 20 is connected to the front end of the tray, and is slidably mounted in the 90 front side of the casing, said rod being bent in loop form, to provide a handle, and being extended rearwardly thru the casing to provide a plunger 21, for a purpose to be explained. A package support 22 is provided, 100

which consists of a wire bent in bail form and comprising a pair of arms, which are pivotally suspended at 23 in opposite sides of the magazine, and a horizontal intermediate portion, or cross bar which is arranged to swing beneath the rear end of the bottom package in the stack, and is normally held against the rear side of the tray by a spring 24, the arrangement being such that said horizontal portion will swing approximately at the level of the top edges of the tray, and will be swung forwardly beneath the stack of packages for a short distance, as the tray is drawn forwardly, as hereinafter explained. A pair of springs 25 are connected at one end to each side of the tray and at their opposite ends to the rear portion of the casing, for returning the tray to its initial position after it has been pulled forward to deliver a package. A pawl 26 is pivoted to the casing and is arranged to engage a series of ratchet teeth 27 on one side of the tray, to prevent return of the tray after it has been partly pulled out, but permitting return thereof after the tray has been pulled out to its delivering position.

The casing is provided with a horizontally disposed bottom support 28, which is so arranged that, when the tray is in its normal or retracted position, it will hold the bottom 30 against the lower edges of the sides of the tray so as to close the same, and a partition 29 is extended from the front end of the support 28 to the bottom of the casing, in front of the delivery opening therein, said support and partition extending the entire 35 width of the casing to form the bottom of a closed passage leading from the magazine to said delivery opening.

A roller 30 is mounted in a pair of ears 40 formed with the rear side of the tray at the middle thereof, said roller being arranged to run on a track formed on the support 28 and to support the tray, so that its guide lugs 14 will not frictionally engage the frame and 45 the weight of the tray will be borne by said roller, so that the movements of the tray will be but slightly retarded by friction.

An ejector is provided, which comprises a finger 32 mounted on a pivot 33 in the frame, 50 said finger being normally supported in an approximately horizontal position by a depending projection 34, which is integrally formed with the finger and extends from the under side thereof in position to engage the 55 pull rod 20. The lower edge of said projection 34 is curved to provide a convex engaging face. An arm 35 is formed integrally with the finger 32 and extends at right angles thereto in position to be engaged by the 60 front side of the tray, the arrangement being such that, when the tray is drawn forwardly, the finger 32 will ride over the front side of the tray, as shown in Fig. 6, and, then, as the tray is drawn forwardly still further, 65 the front side of the tray will engage the

arm 35 and cause the finger 32 to be swung downward into the tray, as shown in Fig. 7.

A cup shaped follower 36, of substantial weight, is provided, which is adapted to rest on the top package of the stack and is fitted 70 to the chamber therefor. As shown in Fig. 4, a pair of arms 37 are mounted on pivots 38, secured in the rear side of the follower, said arms being extended cross wise, each over the pivot of the other, and one of said 75 arms having a screw 39 fixed therein and extending thru a slot 40 in the other arm, so that, when said arms are swung on their pivots, within certain limits, they will be constantly held at similar angles to the horizontal. Said arms are adapted to swing freely, and the pivot of one serves as a stop to limit the downward swinging movement thereof. The length of said arms is such that, when in their lowest position, their end 80 portions project beyond the sides of the follower into position to engage the sides of the magazine. With this arrangement, therefore, when the follower is placed in the top of the magazine, the ends of the arms 37 will 85 engage the sides thereof, as shown in Fig. 4, but will in no way impede the downward movement of the follower. Any force, however, tending to cause the follower to move upward, particularly at its rear end, will 90 cause the arms to be immediately frictionally engaged with the sides of the magazine and thus prevent any appreciable upward movement thereof. The purpose of this arrangement will be explained. The follower 95 also has a bar or handle 41, which is secured to the rear side thereof and projects beyond its front side to form a finger 42, which latter acts to engage the coin controlled apparatus, with which the machine is associated, 100 when the magazine is empty, to cause the return of the coin to the purchaser.

When the follower is to be removed to permit refilling of the magazine, the arms 37 are swung upwardly against the handle 41, 105 permitting ready removal by lifting on the latter.

Suitable locking means not shown are provided for preventing forward movement of the tray, except when released by the coin 110 controlled mechanism.

In practice the magazine will be filled to a suitable extent, as indicated in Fig. 2, and the follower 36 placed in position thereon. As in the retracted position of the tray, it will 115 be in register with the magazine, the bottom package in the stack will be contained in the tray and supported on its bottom and the top surface of this package will be flush with the top edges of the sides of the tray. When the tray is drawn forward, this package 120 will be carried from beneath the stack as the tray is advanced, and, as soon as the tray has been advanced a short distance, the roller 125 17 will be carried beneath the bottom pack- 130

age of the stack so that, during the first part of the delivery movement, the stack of packages will be supported by the roll 17 and by the package which is being discharged, as shown in Fig. 6. Also, as the tray is moved forward, the support 22, which is normally held against its rear side will swing forward until its horizontal portion is carried beneath the bottom package of the stack, its motion being arrested in the position of Fig. 6. When the tray has been moved forward to the position of Fig. 7, in which the hinge 16 of the bottom 15 is at the front end of the horizontal support 28, the bottom will swing downward against the inclined bottom 29, by its own gravity and the gravity of the package, permitting the latter to slide down the inclined surface, thus provided, into the chute 11, where it may be readily removed. As the tray is moved into the delivery position of Fig. 7, the front side of the tray will engage the arm 35 and cause the finger 32 to be swung downward, so that, in case a package should become flattened, so that it engaged the sides of the tray so closely that it would not fall by its gravity from the tray when it is permitted to do so by the downward swinging of the bottom, then the finger 32 will be pressed downward against the package at its front end, and will positively force it downward from the tray, so that delivery thereof will be insured.

As shown in Fig. 7, when the tray is in its extreme forward position and a package has just been delivered, a small portion of the next package will be exposed, so that, if it should be attempted to remove this package while the tray is held in the advanced position, the space provided therefor will be so small that it would be impossible to do this ordinarily without crushing the package. If, however, only one or two packages remained in the stack, it would be possible to remove the bottom package by tilting its rear end upward, so that the package could be drawn down thru the opening in an inclined direction. Such tilting will however be prevented by the follower 36, which is positively locked against such tilting movement by the arms 37 and therefore firmly holds the package down on the wire support 22, and roll 17, so that it will not be possible to remove the package without at least seriously mutilating it. Also, when the tray is permitted to return to its initial position, the roll 17 will sustain the stack during this movement while the bottom package in the stack will be prevented by the follower from tilting downward at its front end on the roll as a pivot, so that the package will be held in a horizontal position, until the roll 17 has been nearly moved from beneath the package. As the return motion will usually be rapid, ordinarily the package will fall into the tray while held in a horizontal position, but, if the front end of

the bottom package should swing down slightly, it will nevertheless be forced into a flat position in the tray by gravity.

While the package will usually slide down the bottom 15 when in its inclined position, and be delivered to the chute 11, so that it will slide down the same and be held by the lip which is provided at the end of the chute, if the package is relatively light it sometimes only slides part way down the chute, so that, when the tray moves back and its bottom is swung up, the bottom will engage the package and tip it up on its front end. When this occurs the plunger 21 will immediately thereafter engage the top of the package and tilt it back, so that it will slide down the chute to its lip.

The means 22, for supporting the bottom package of the stack at its rear end, so that it cannot swing down below the level of the roll 17, is an important feature of the invention, as, otherwise, the bottom package would be liable to swing down to such an extent that the roll 17 would crush the package on the return movement. Moreover, the use of the locking means on the follower makes it necessary to avoid lifting the packages to any extent after they have once moved down.

I claim:

1. A machine for successively delivering flat sided packages from the bottom of a stack of such packages, comprising a casing having a magazine in which the packages are stacked horizontally, a horizontally disposed tray having a chamber adapted to contain a package and open at its upper end to permit the package to fall vertically therein, said tray being horizontally movable between a package receiving position beneath the magazine and a delivering position in front thereof, a main package support mounted on the rear end of the tray and movable therewith in position to engage the under side of the bottom package of the stack, to support the same as the tray is moved forwardly to deliver the package therein, and a supplemental package support arranged to be automatically moved beneath the rear end portion of such bottom package during the first part of said forward movement of the tray, to support said end portion until said main support is moved adjacent thereto as the tray is returned to receiving position.

2. A machine for successively delivering flat sided packages from the bottom of a stack of such packages, comprising a casing having a magazine in which the packages are stacked horizontally, a horizontally disposed tray having a chamber adapted to contain a package and open at its upper end to permit the package to fall vertically therein, said tray being horizontally movable between a package receiving position beneath the magazine and a delivering position in front

- thereof, package supporting means mounted on the rear end of said tray and having a face disposed at the level of the top edges of the tray in position to engage the under side of the bottom package in the stack and support the same as the tray is moved forward to deliver the package therein, and supplemental supporting means for sustaining the rear end portion of said bottom package while the tray is in its advanced positions.
3. A machine for successively delivering flat sided packages from the bottom of a stack of such packages, comprising a casing having a magazine in which the packages are stacked horizontally, a horizontally disposed tray having a chamber adapted to contain a package and open at its upper end to permit the packages to fall vertically therein, said tray being horizontally movable between a package receiving position beneath the magazine and a delivering position in front thereof, a package supporting means mounted on the rear end of said tray and having a package engaging face disposed at the level of the top edges of the tray and extending for the width of said chamber and means for supporting the rear end of the bottom package of the stack while the tray is in its delivering position.
4. A machine for successively delivering flat sided packages from the bottom of a stack of such packages, comprising a casing having a magazine in which the packages are stacked horizontally, a horizontally disposed tray having a chamber adapted to contain a package and open at its upper end to permit the packages to fall vertically therein, said tray being horizontally movable between a package receiving position beneath the magazine and a delivering position in front thereof, package supporting means mounted on the rear end of the tray and having a package engaging face at the level of the top edges thereof and a supplemental package support arranged to be automatically moved beneath the stack, as the tray is moved forward to support the bottom package therein at its rear end while its front portion is supported on said face.
5. A machine for successively delivering flat sided packages from the bottom of a stack of such packages, comprising a casing having a magazine in which the packages are stacked horizontally, a horizontally disposed tray having a chamber adapted to contain a package and open at its upper end to permit the packages to fall vertically therein, said tray being horizontally movable between a package receiving position beneath the magazine and a delivering position in front thereof, a roll journaled on the tray at the rear end of said chamber in position to roll in contact with the under surface of the bottom package of the stack and to sustain the same as the tray is moved forward, and a supplemental package supporting means automatically movable beneath the rear end of the bottom package, to sustain the rear end thereof in an advanced position of the tray.
6. A machine for successively delivering flat sided packages from the bottom of a stack of such packages, comprising a casing having a magazine in which the packages are stacked horizontally, a horizontally disposed tray having a chamber adapted to contain a package and open at its upper end to permit the packages to fall vertically therein, said tray being horizontally movable between a package receiving position beneath the magazine and a delivering position in front thereof, a main package support mounted on the rear end of the tray and movable therewith in position to engage the under side of the bottom package of the stack, to support the same as the tray is moved forwardly to deliver the package therein, and a supplemental package support normally actuated to move from a position in the rear of the stack to a position to engage the under side of the rear portion of said bottom package as the tray is moved forwardly from its receiving position.
7. A machine for successively delivering flat sided packages from the bottom of a stack of such packages, comprising a casing having a magazine in which the packages are stacked horizontally, a horizontally disposed tray having a chamber adapted to contain a package and open at its upper end to permit the packages to fall vertically therein, said tray being horizontally movable between a package receiving position beneath the magazine and a delivering position in front thereof, a main package support mounted on the rear end of the tray and movable therewith in position to engage the under side of the bottom package of the stack, to support the same as the tray is moved forwardly to deliver the package therein, a cross bar extending for the width of the magazine and pivotally suspended and spring actuated to swing from a position in the rear thereof to a position beneath its lower end, to support the rear end portion of said bottom package while the tray is being moved to its delivering position and being returned therefrom.
8. A machine for successively delivering flat sided packages from the bottom of a stack of such packages, comprising a casing having a magazine in which the packages are stacked horizontally, a horizontally disposed tray having a chamber adapted to contain a package and open at top and bottom to permit the packages to pass vertically therein and to be discharged therefrom, means permitting reciprocal movement of the tray between a receiving position beneath the stack and a delivering position in front thereof, a main package support mounted on the rear end of the tray and movable therewith in position to engage the under side of the bottom package of the stack, to support the same as the tray is moved forwardly to deliver the package therein, a cross bar extending for the width of the magazine and pivotally suspended and spring actuated to swing from a position in the rear thereof to a position beneath its lower end, to support the rear end portion of said bottom package while the tray is being moved to its delivering position and being returned therefrom.

- and a delivering position in front thereof, a bottom pivoted to the rear end of the tray and adapted, when held horizontally, to close the lower end of said chamber, means permitting said bottom to swing downwardly when the tray is moved to delivering position, and an ejector device arranged to be automatically moved downwardly into said chamber as the tray is moved into delivering position to force the package from the chamber. 5
9. A machine for successively delivering flat sided packages from the bottom of a stack of such packages, comprising a casing having a magazine in which the packages are stacked horizontally, a horizontally disposed tray having a chamber adapted to contain a package and open at top and bottom to permit the packages to pass vertically therein and to be discharged therefrom, means permitting reciprocal movement of the tray between a receiving position beneath the stack and a delivering position in front thereof, a bottom pivoted to the rear end of the tray and adapted, when held horizontally, to close the lower end of said chamber, means permitting said bottom to swing downwardly when the tray is moved to delivering position and an ejector device arranged to be automatically moved downwardly to engage the top side of a package in said chamber to eject the same therefrom as the tray is moved to its delivering position. 10
10. A machine for successively delivering flat sided packages from the bottom of a stack of such packages, comprising a casing having a magazine in which the packages are stacked horizontally, a horizontally disposed tray having a chamber adapted to contain a package and open at top and bottom to permit the packages to pass vertically therein and to be discharged therefrom, means permitting reciprocal movement of the tray between a receiving position beneath the stack and a delivering position in front thereof, a bottom pivoted to the rear end of the tray and adapted, when held horizontally, to close the lower end of said chamber, means permitting said bottom to swing downwardly when the tray is moved to delivering position, to move said finger downwardly into the front end of said chamber to eject the package therefrom. 15
11. A machine for successively delivering flat sided packages from the bottom of a stack of such packages, comprising a casing having a magazine in which the packages are stacked horizontally, a horizontally disposed tray having a chamber adapted to contain a package and open at top and bottom to permit the packages to pass vertically therein and to be discharged therefrom, means permitting reciprocal movement of the tray between a receiving position beneath the stack and a delivering position in front thereof, a bottom pivoted to the rear end of the tray and adapted, when held horizontally, to close the lower end of said chamber, means permitting said bottom to swing downwardly when the tray is moved to delivering position to force the package from the chamber. 20
12. A machine for successively delivering flat sided packages from the bottom of a stack of such packages, comprising a casing having a magazine in which the packages are stacked horizontally, a horizontally disposed tray having a chamber adapted to contain a package and open at top and bottom to permit the packages to pass vertically therein and to be discharged therefrom, a follower adapted to rest on the top package of the stack and to move downwardly therewith, and a pair of crossed arms pivoted to the follower at their lower ends and having their opposite ends arranged for frictional engagement with the sides of the magazine to lock the follower against upward movement in all positions 25
13. A machine for successively delivering flat sided packages from the bottom of a stack of such packages, comprising a casing having a magazine in which the packages are stacked horizontally, a horizontally disposed tray having a chamber adapted to contain a package and open at its upper end to permit the packages to fall vertically therein, said tray being horizontally movable between a package receiving position beneath the magazine and a delivering position in front thereof, package supporting means mounted on the rear end of said tray and having a face disposed at the level of the top edges of the tray 30
14. A machine for successively delivering flat sided packages from the bottom of a stack of such packages, comprising a casing having a magazine in which the packages are stacked horizontally, a horizontally disposed tray having a chamber adapted to contain a package and open at its upper end to permit the packages to fall vertically therein, said tray being horizontally movable between a pack- 35

age receiving position beneath the magazine and a delivering position in front thereof, package supporting means mounted on the rear end of said tray and having a face disposed at the level of the top edges of the tray 5 in position to engage the under side of the bottom package in the stack and support the same as the tray is moved forward to deliver the package therein, means for supporting the rear end of said bottom package while the 10 tray is in an advanced position, a follower adapted to rest on the top package of the stack and to move downward in said magazine, and a locking device on said follower arranged for frictional engagement with a fixed part of 15 the casing to lock the follower against upward movement in all positions thereof.

15. A machine for successively delivering flat sided packages from the bottom of a stack of such packages, comprising a casing having 20 a magazine in which the packages are stacked horizontally, a horizontally disposed tray having a chamber adapted to contain a package and open at top and bottom to permit the packages to pass vertically therein and to be 25 discharged therefrom, means permitting reciprocal movement of the tray between a receiving position beneath the stack and a delivering position in front thereof, a bottom 30 pivoted to the rear end of the tray and adapted, when held horizontally, to close the lower end of said chamber, means permitting said bottom to swing downwardly when the tray is moved to delivering position, and means 35 connected to the tray, arranged to engage the top portion of the package after it has been delivered, to tilt it rearwardly as the tray is moved rearward from its delivering position.

In testimony whereof, I have signed my name to this specification.

40 ARTHUR H. DU GRENIER.
